INVENTOR
WILLIAM A. ROBINSON
BY HIS ATTORNEY

A. E. Carlson:

UNITED STATES PATENT OFFICE.

WILLIAM A. ROBINSON, OF MINNEAPOLIS, MINNESOTA.

BARREL-HANDLING DEVICE.

1,335,796.

Specification of Letters Patent.

Patented Apr. 6, 1920.

Application filed December 2, 1919. Serial No. 341,963.

To all whom it may concern:

Be it known that I, WILLIAM A. ROBINSON, a citizen of the United States, residing at Minneapolis, in the county of Hennepin and State of Minnesota, have invented certain new and useful Improvements in Barrel-Handling Devices, of which the following is a specification.

My invention relates to barrel handling devices and the object is to provide simple yet efficient means for emptying any desired part of the contents of a barrel or other container without tipping and again righting the barrel with the hands in the usual awkward and tiring way. The invention is clearly illustrated in the accompanying drawing, in which:

Figure 1 is a side view of my barrel handling device and a barrel secured therein.

Fig. 2 is a view similar to Fig. 1 but showing the barrel in a lifted position.

Fig. 3 is a view similar to Fig. 2 but showing the barrel in a tilted position.

Fig. 4 shows the lower part of the device complete as seen from the right in Fig. 1.

Fig. 5 is a sectional detail view on the line 5—5 in Fig. 4.

Referring to the drawing by reference numerals 6 designates a main frame having an upright 7 secured to each side thereof, said uprights being retained in fixed vertical positions by braces 8. In each upright member 7 is secured a stud 9 on which is pivotally and slidably mounted a barrel gripping frame 10 having slots 11 therein adapted to be slidably and pivotally engaged by said studs 9. Intermediate the frame 10 and one of the upright members 7 is pivotally mounted also upon the stud 9 a lever arm 12 having a handle 13 at one end thereof. The other end of said lever arm 12 is pivotally connected by a link 14 to the lower end of the frame 10.

A barrel is inserted in the frame 10 by opening and again closing suitable clasps 15. The barrel and tipping device normally rests in the position shown in Fig. 1. When it is desired to empty a part of the contents of the barrel the lever arm is pulled down until it catches under a projection 16 on the frame 10. The device then is in the position shown in Fig. 2. The barrel can then conveniently be tipped (see Fig. 3) in the desired angle, after which it is again

righted and by bending the lever 12 slightly 55 to one side the same will be released and the barrel can be again lowered to the floor.

Having now fully shown and described my invention what I claim to be new and 60 desire to protect by Letters Patent is:

1. A device of the class described consisting of a main frame having fixed thereto inwardly disposed studs, a secondary frame tiltably and slidably mounted on said 65 studs, a lever arm pivotally mounted on one of said studs, operative connection between said lever arm and said secondary frame whereby manipulation of the former will raise and lower the latter in the main frame. 70

2. A device of the class described consisting of a main frame, a secondary frame tiltably and slidably mounted in said main frame, a lever arm pivotally mounted on said main frame and link connection between 75 said lever arm and said secondary frame whereby manipulation of the former will raise and lower the latter in the main frame.

3. A device of the class described consisting of a main frame, oppositely placed inwardly disposed studs fixed to said frame, a secondary frame having slots adapted to be engaged by said studs, a lever arm pivotally mounted on one of said studs, operative 85 connection between said lever arm and said secondary frame whereby manipulation of the former will raise and lower the latter in the main frame. 80

4. A device of the class described consisting of a main frame, oppositely placed inwardly disposed studs fixed to said frame, a secondary frame tiltably and slidably mounted in said main frame on said studs, a lever arm pivotally mounted on one of said 95 studs, a link pivotally mounted at one end to said lever arm and at the other end to said secondary frame. 90

5. A device of the class described consisting of a main frame, a secondary frame 100 tiltably and slidably mounted in said main frame, a lever arm pivotally mounted on said main frame, a link pivotally mounted at one end to said lever arm and at the other end to said secondary frame. 105

In testimony whereof I affix my signature.

WILLIAM A. ROBINSON.
